UNITED STATES PATENT OFFICE.

CHARLES W. MEADOWCROFT, SR., OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

KEY-BEARING FOR LOCKS.

1,286,704.

Specification of Letters Patent.

Patented Dec. 3, 1918.

Application filed July 10, 1918. Serial No. 244,267.

To all whom it may concern:

Be it known that I, CHARLES W. MEADOWCROFT, Senior, a citizen of the United States, residing in Philadelphia, Pennsylvania, have invented certain Improvements in Key-Bearings for Locks, of which the following is a specification.

My invention relates to certain improvements in key bearings of locks of the type known as "cupboard" or "drawer" locks. These locks are usually made with a long barrel projecting from the casing through the woodwork of the door, or drawer, the end of this barrel being exposed through the outside of the door, while the casing of the lock is secured on the inside.

One object of my invention is to provide a key bearing which is adapted to rotate in this barrel and to support the key so that it will properly actuate the mechanism of the lock.

A further object of the invention is to manufacture the key bearing from sheet metal bent into shape.

25 In the accompanying drawings:

Figure 1 is a face view of a cupboard lock to which my invention is applied;

Fig. 2 is a rear view of the casing;

Fig. 3 is a transverse sectional view on the line 3—3, Fig. 1, the mechanism within the casing, with the exception of the key bearing, being omitted.

Fig. 4 is a perspective view of the key bearing;

35 Fig. 5 is a plan view;

Fig. 6 is a side view;

Fig. 7 is a front view;

Fig. 8 is a rear end view;

Fig. 9 is a perspective view of a portion of 40 the key which is adapted to the key bearing; and

Fig. 10 is a view of the blank from which the key bearing is formed.

The casing of the lock has a body portion 45 1 and a cover plate 2 to which is secured the barrel 3. This barrel is of different lengths, according to the thickness of the woodwork of the door, or drawer, so that while the lock is secured to the inner side 50 of the door, or drawer, the outer end of the barrel is flush with the outer surface thereof.

Mounted within the barrel is a key bearing 4, made as shown in Fig. 4, having a cylindrical end portion 5, which is of the same 55 diameter as the interior of the barrel and

fits against the internal flange 6 at the outer end of the barrel, the flange holding it against outward movement.

7 is a key slot formed in the end portion 5 and this end portion has a depression 8, 60 as shown, forming a guide for the key. The slot conforms to the notch 9 in the flange 6 of the barrel. 10 is a downwardly projecting bottom support for the key, bent, as shown in Fig. 6, so as to be in line with the 65 bottom of the slot 7. At the end of this bottom support are shoulders 11 which fit against the body portion 1 so as to hold the key bearing against longitudinal movement in the casing. Projecting beyond the 70 shoulders is a bearing portion 12 having upturned flanges 13, which are spaced apart to form the rear keyway. This portion is rounded so as to fit the circular opening in the body portion, as clearly shown in Fig. 2. 75

In order to form a guide for the key in addition to the guide to the end portion 5, I provide arms 14, which are bent inward, as shown in Fig. 5, and are spaced apart sufficiently to allow for the passage of the key. 80 These arms are preferably bent outward so that their ends 15 will fit against the interior of the barrel 3 and will act to steady the key support in the barrel and will also act to hold the key bearing in the position 85 in which the key leaves it.

My improved key bearing is made from sheet metal cut in the form shown in Fig. 10 and the parts are bent on the dotted lines to form the bearings shown in Figs. 4, 5 and 6. 90

From the above description it will be seen that I can make a key bearing for a lock from sheet metal bent into shape which will be comparatively cheap as very little metal is employed and which will provide means 95 for properly guiding the key and will be firmly supported in the lock casing.

I claim:

1. The combination in a lock, of a casing having a barrel; a key center mounted in the barrel and having a slotted end section adapted to close the end of the barrel; and having a rearwardly extending bottom support terminating in a shoulder fitting against the body portion of the casing and 105 also having a flanged extension fitting an opening in the said body portion.

2. The combination in a lock, of a casing having a cylindrical barrel, said barrel having a notched internal flange; a key bearing 110

mounted in the barrel and having an end portion fitting against the flange thereof, the said end portion being slotted and arranged to align with the notch in the flange 5 of the barrel and having a rearwardly extending bottom support arranged in line with the bottom of the slot in the end portion and having a reduced flanged portion extending into an opening in the body of 10 the lock and having flanges bearing against the inner surface of the body portion, whereby the bearing is held against longitudinal movement in the lock, but is free to rotate therein.

15 3. A key bearing for a lock made of a single piece of metal bent into shape and having a bottom key support extending its full length and having at one end a slotted end portion and having at the opposite end 20 a reduced projection slotted to fit the key, said slot being in a line with the slot in the opposite end portion and forming shoulders on the key support at each side of said projection, said shoulders being arranged to fit 25 against the casing of the lock.

4. A key bearing for a lock having a slotted end portion; a rearwardly extending key support having shoulders at its rear end; a flanged extension beyond the shoulders; and arms projecting rearwardly from the end portion and bent to form a key support midway between the end portion and the rear support.

5. A key bearing for a lock having an end

portion slotted for the passage of the key 35 and a rearwardly extending bottom support bent so as to be in line with the bottom of the slot in the end portion and having a shoulders at the outer end and having a flanged portion beyond the shoulders forming a rear key guide; and a trunnion for the key bearing.

6. The combination in a lock, of a casing having a cylindrical barrel flanged at its outer end and notched; a key bearing 45 mounted in the lock and extending into the barrel; said key bearing having a slotted end portion fitting against the flange of the barrel; a rear extension forming shoulders fitting against the rear of the body portion and having a flanged projection forming a trunnion extending into an opening in the body portion forming the rear support for the bearing, the rear extension having a bottom support for the key; and arms projecting inwardly from each side of the end portion and forming an intermediate key guide, said arms having projecting ends fitting the barrel and forming a mid support for the bearing in the barrel between the two ends.

7. The combination in a lock, of a casing having a barrel; a key bearing mounted in the barrel and having an arm bearing against the interior wall of the barrel, tending to hold frictionally the key bearing in position.

In witness whereof I affix my signature.

CHARLES W. MEADOWCROFT, SR.
